UNITED STATES PATENT OFFICE.

ALEXANDER LYSAGHT DALY, OF STAPLETON, NEW YORK.

PROCESS AND APPARATUS FOR DRYING VENEER.

Application filed January 3, 1920. Serial No. 349,258.

To all whom it may concern:

Be it known that I, ALEXANDER L. DALY, a citizen of the United States, residing at Stapleton, in the county of Richmond, State of New York, have invented certain new and useful Improvements in Processes and Apparatus for Drying Veneer; and I do hereby declare the following to be a full, clear, and exact description of the invention, such as will enable others skilled in the art to which it appertains to make and use the same.

This invention relates to an improved method and apparatus for drying veneer in a uniform continuous manner.

In the drying of veneer at the present time, it is customary to pass the sheets of veneer, carried by a belt or belts, between a long series of heated rolls. Veneer driers of this character require a large floor space and are expensive to construct and operate.

The improved apparatus of the present invention is simple and inexpensive in construction and operation and overcomes the objections to veneer driers heretofore commonly used. The improved veneer drier of the present invention occupies a relatively small floor space and can be easily constructed and operated. The improved process of drying veneer, as practiced in this improved apparatus, subjects the veneer sheets or strips to a continuous and uniform drying operation, followed by a subsequent cooling operation, whereby the dried and cooled veneer strips or sheets are discharged at the end of the drying and cooling operation in a condition adapted for immediate storage.

In the manufacture of veneer, it is customary to use logs of considerable length, for example, around 17 feet long. These logs are commonly quartered, and, after squaring or trimming to remove the bark and outer edgings or slabs, are cut or sawed into sheets of veneer having a length equal to the length of the log, and having a width varying with the size of the log. The sheets of veneer thus produced may, for example, have a length of about 17 feet, a width of about 10 inches, more or less, and a thickness of as little as one-thirtieth-second of an inch or less, the thickness of the sheet vary-

ing with the character of wood and the use to which the veneer is to be put. Inasmuch as veneer is commonly cut or sawed from green logs, it becomes of importance to provide for the uniform drying of the veneer sheets or strips in a continuous manner.

According to the present invention, the thin sheets or strips of veneer are fed edge-wise between belts, or series of belts, passing over one or more series of rolls and subjected to the heating and drying action of hot air or other heating means; and the sheets are then passed through a cooling zone where they are cooled by exposure to the atmosphere or artificial cooling means, and then discharged in a cooled and dried condition so that they can be immediately stacked, shipped, or used.

The invention will be further described in connection with the accompanying drawings illustrative of one form of apparatus embodying the invention and adapted for the practice of the process of the invention, but it is intended and understood that the invention will be illustrated by, but is not limited to, the specific embodiments thereof so illustrated and described.

In the accompanying drawings—
80

Fig. 1 is a vertical, longitudinal, sectional view, of a somewhat diagrammatic character, illustrating the improved veneer drier; and

Fig. 2 is a vertical, transverse, sectional view taken on the line 2—2 of Fig. 1.

The apparatus illustrated has a frame work of suitable material of which the upright end members are indicated at 1 and 2, the top beams at 3, and the beams for the feed platform at 4. Mounted upon the frame members 4 are bearings supporting the rolls 5 and 6 arranged at different levels as shown. A feed table 7^a is arranged below the roll 6 and in advance of the top of the roll 5.

Suitably supported by the frame members or extensions thereof are two series of rolls, the rolls 7, 9 and 12, 11 and 11^a being arranged at one end of the apparatus, and the rolls 8, 10 and 13 at the other. Mounted upon these rolls are two series of belts 14 and 15. The top belts 14 pass around the feed roll 6 and thence successively around

the rolls 7, 8, 9, 10, 12 and 13, and back to the feed roll 6. The lower belts 15 pass around the lower feed roll 5 and thence successively around the rolls 7, 8, 9, 10, 11 5 and 11^a, and back to the feed roll 5. These belts, as shown, are not laterally continuous, but are spaced apart at regular intervals, the narrow belts of the top series alternating with the narrow belts of the lower 10 series, and providing a space therebetween.

The thin sheets or strips of veneer are fed edgewise upon the lower series of belts as they pass over the feed table 7^a and are carried by this lower series of belts beneath 15 the roll 6, and thence between the two series of belts around the rolls 7, 8, 9 and 10 and are finally discharged from the carrying belts upon the discharge table or receiving platform 28.

20 The lower portion of the apparatus, and the lower rolls and portions of the belts carried thereby, are enclosed within the drying casing or chamber or compartment 16. The walls of this chamber or compartment are 25 made of metal or wood or other suitable material and are provided with a suitable inlet for the introduction of fresh air and a suitable outlet for the withdrawal of the hot, moist air. A conventional inlet 17 is shown 30 at the bottom of the chamber at one end thereof; and a conventional outlet 18 is shown at the top of the compartment at the opposite end, this opening 18 having the discharge conduits 19 and 19^a connected thereto, which conduits in turn lead to the 35 exhaust fan 20. Slotted openings 24, 25 and 26 are also provided for the passage of the belts, and openings 24 and 25 also for the veneer carried thereby, through the walls of 40 the compartment or chamber. Within the compartment or chamber, and preferably arranged between the successive levels of the belts carrying the veneer are heating pipes 21, having suitable manifold and feed pipes 22, 23. The number and arrangement of 45 these heating pipes or coils is, of course, capable of variation and regulation.

In the operation of the apparatus, and the practice of the improved drying process, the thin sheets or strips of veneer are 50 fed edgewise, in the manner above described, between the upper and lower series of belts, and are thence carried between these two series of belts around the rolls 7, 8, 9 and 10. 55 The air within the drying compartment is suitably heated by means of the heating coils or pipes 21 and this heated air is circulated through the drying compartment or chamber. The fresh air is thus introduced 60 near the bottom of the compartment through the opening 17 and is heated by its passage over the heating coils. The heated air comes in contact with the thin sheets of veneer and dries them in a progressive manner. Inasmuch as the supporting belts are relatively 65

narrow and are spaced apart, a considerable portion of the veneer sheets will be left exposed to the direct drying action of the heated air. Moreover, the upper and lower belts alternate with each other so that the 70 entire length of the veneer strips will be exposed either on one side or the other. The belts are preferably of canvas or fabric permitting the circulation of air therethrough so that they do not interfere with the desired heating and drying action. As the 75 veneer strips are carried around the end rolls, they are reversed so that the upper sides of the veneer strips then become the lower sides. In this way, the heated air acts directly upon first one side of the strips and then the other side alternately as the strips are carried successively around the various rolls. Furthermore, the strips are kept in motion so that, should portions of the drying 80 chamber or compartment be warmer than others, or should a stronger current of heated air be passing through certain portions of the compartment, the strips will all nevertheless be subjected to the same drying 85 action because all of the successive strips will be passed through the drying compartment in the same manner.

The veneer strips leave the drying compartment through the slotted opening 25 and 90 then pass around the roll 10 and to the discharge platform or conveyor 28. As the strips leave the drying compartment in a still heated condition they are subjected to the cooling effect of the outside atmosphere, 95 supplemented by any additional cooling means that may be desired, and this cooling action continues while the strips are being passed to the point of discharge. In this manner the strips are thoroughly cooled and 100 freed from the heat imparted to them in the drying compartment. Furthermore, the cool air, in cooling the strips, exerts a further 105 drying influence.

At the discharge platform or conveyor 28 110 the strips are removed from the lower belt 15 by means of fingers 29, which, as shown, extend part of the way around the roll 11 so that the veneer strips will be forced upon the receiving table or conveyor 28 as the 115 successive strips are discharged by the belt.

In the diagrammatic illustration of Fig. 1, only a few veneer strips 27 are shown, and these are spaced apart at more or less regular intervals, but it will be understood that 120 in practice the strips are fed continuously into the machine and that only a sufficient space will be left between the adjacent strips to permit the desired circulation of air therebetween.

Power for driving the apparatus can be supplied from any suitable source. In the apparatus illustrated, the power is applied through the belt 30 to the roll 7 and thence through the belt 31 to the roll 9, so that both 130

the rolls 7 and 9 act as driving rolls. The number of rolls to which the driving means is connected can, of course, be varied depending upon the power required for operating 5 the apparatus. Ordinarily, however, this power will be relatively small.

The rolls which carry the belts are conventionally shown as solid rolls, but it will be evident that these rolls need not have any 10 considerable strength or weight, provided

they have a sufficient strength to support the belts and the veneer carried thereby. Open-work rolls having a suitable periphery for the belts will operate in a similar manner.

15 In order to assist in guiding the two series of belts, one or more of the rolls may be provided with guide projections, or with depressions. Guide depressions are shown on roller 13 in Fig. 2, while similar depressions 20 (not shown) may be provided on roller 11^a.

In the operation of the drying apparatus it will be understood that the heat applied can be varied by increasing or decreasing the 25 number of heating pipes or coils or by increasing or decreasing the temperature of the heating medium. The drying effect can also be regulated by increase or decrease of the draft through the apparatus.

The size of the rolls 7, 8, 9 and 10, around 30 which the veneer is carried between the upper and lower series of belts, is such that the veneer will pass around the rolls without being subjected to undue bending. Such bending as is incident to passing around 35 these rolls will be withstood by the veneer without any objectionable cracking thereof, due to the fact that the veneer is fed edgewise, so that the bending of the veneer sheets is with the grain rather than across 40 it. As above noted, the veneer strips may have a length of 17 feet or more and a width of only about 10 or 12 inches. The apparatus should therefore have a sufficient width to permit the long sheets to be fed 45 sidewise therethrough. That is, the apparatus should have a greater width than the maximum length of the veneer sheets.

I claim:

1. The method of drying veneer which 50 comprises feeding the veneer sheets edgewise between upper and lower belts, carrying the veneer between the belts through a drying compartment and, during such carriage, periodically reversing the position of 55 the sheets of veneer to bring their opposite faces alternately uppermost.

2. The method of drying veneer, which 60 comprises feeding the veneer sheets edgewise between upper and lower belts, with the grain of the veneer substantially perpendicular to the direction of belt travel and passing the veneer so carried back and forth around a series of rolls in a drying compartment.

65 3. The method of drying veneer, which

comprises feeding the veneer sheets edgewise between upper and lower belts, carrying the veneer between the belts back and forth around successive rolls in a drying compartment and there subjecting the same to the 70 drying action of heated air, then carrying the veneer between the belts through cool air, to remove the heat imparted by the drying, and discharging the dried and cooled veneer from between the belts. 75

4. An apparatus for drying veneer, comprising a series of rolls, series of upper and lower endless belts arranged around said rolls and between which the veneer is to be carried, the belts in one set being staggered with respect to those of the other set, means for operating said rolls and belts, a drying chamber or compartment enclosing part of 80 said rolls and the belts and veneer carried thereby, and a part of the rolls and belts being outside said drying compartment to permit cooling of the dried veneer before discharge from between the belts. 85

5. An apparatus for drying veneer, comprising two series of rolls, one near each end 90 of the apparatus, two series of endless belts arranged to rotate around said rolls, a drying compartment enclosing the lower rolls and the belts carried thereby, means for circulating a current of heated air through 95 said compartment, and the upper rolls and upper portions of the belts being outside said drying compartment and exposed to the cooling action of cool air. 100

6. An apparatus for drying veneer, comprising two series of rolls, two series of narrow endless belts spaced apart and carried by said rolls, between which the veneer is adapted to be carried, the belts of one series alternating with those of the other so that the veneer only comes in contact with one belt of each series at any particular point of its length. 105

7. The method of drying veneer which 110 comprises moving the sheets in edgewise relation through a drying compartment and, during such movement, causing the sheets to pass from one side of the compartment to the other and to traverse a curving path in reversing the direction of this side to side 115 movement, the sheets being maintained at all times with their grain substantially at right angles to the direction of their progress through the compartment whereby the sheets may be bent at each change of direction without liability of breaking. 120

8. In an apparatus of the character specified, a drying chamber, means for carrying the veneer through the chamber and arranged to engage the opposite faces of the 125 sheets over restricted areas at points relatively far apart and staggered on the opposite faces.

9. In an apparatus of the character specified a drying chamber, means for carrying 130

the veneer through the chamber and arranged to engage the opposite faces of the sheets over restricted areas at points relatively far apart and staggered on the opposite faces, said means being arranged to carry the veneer sheets backwards and forwards through the chamber until they are

dry, and to reverse the veneer at the end of its travel in each direction whereby to subject the opposite faces of the sheets to a uniform drying action.

In testimony whereof I affix my signature.

ALEXANDER LYSAGHT DALY.
